UNITED STATES PATENT OFFICE.

WILLIAM J. BEST, OF DETROIT, MICHIGAN.

HYDROCARBON-BURNER.

1,177,297.

Specification of Letters Patent. Patented Mar. 28, 1916.

Application filed January 6, 1915. Serial No. 771.

To all whom it may concern:

Be it known that I, WILLIAM J. BEST, a citizen of the United States, residing at Detroit, in the county of Wayne and State of Michigan, have invented a new and useful Hydrocarbon-Burner, of which the following is a specification.

This invention relates to means for burning gasoline, kerosene, alcohol and other liquid hydro-carbons that can be readily vaporized, and its object is to provide a burner which will produce an intense fire in minimum time, which shall be simple in construction, and which may be easily and completely controlled.

This invention consists of an inner perforated chimney and a fuel trough integral therewith and provided with an inclined ledge upon which the fuel is received, a fuel supplying device adapted to discharge liquid fuel onto the ledge, and an outer perforated chimney extending down into the trough adjacent the ledge.

It further consists in the details of construction shown in the accompanying drawing and particularly pointed out in the claims.

In the drawing, Figure 1 is an elevation of this improved burner, parts being broken away to disclose the interior construction. Fig. 2 is a central vertical section. Fig. 3 is a plan of a spacing plate.

Similar reference characters refer to like parts throughout the several views.

The burner is made up of an inner cylindrical chimney 1 having holes 2 to permit air to pass through to the flame between it and the outer chimney 3, also perforated to permit the passage of air. A central imperforate tube 4 extends down from the imperforate top 5, and may be provided with a pair of circumferential ribs 6 to hold the circular plate 7 in position, which plate positions the tube 4. The inner chimney 45 may also have two circumferential ribs 8 to hold the ring 9 in position, which ring is provided with inwardly extending arms 10 to position the tube 4, but which permit the free flow of air. See Fig. 3.

Integral with the inner chimney 1 is a trough having sides 12 and 13 and bottom 14, in which trough rests the asbestos ring 15. A ledge 16 is integral with the side 13 and is in turn formed with a cylindrical flange 17. The outer chimney 3 preferably

fits quite tightly within the wall 13. The outer chimney is preferably formed with two circumferential ribs 18 which receive the inner edge of a circumferential baffle-plate between them, the plate consisting of 60 a radial ring 19, conical portion 20 and cylinder 21.

Fuel is supplied to this burner by a connection 23, nipple 24, valve body 25, pipe 26 and elbow 27. In the valve body 25 is 65 mounted a needle-valve 28 having a hand-wheel 29. Any other desired fuel control may be employed. Connected to the elbow 27 is a ring 30 that extends over the cylindrical flange 17 on the ledge 16 and outside 70 of the outer chimney 3, in order to prevent the escape of the fuel vapors as much as possible. A small annular rib 32 on the ledge 16 is adapted to prevent the wetting of the inner side of the flange 17, the flange 75 33 on the ring 30 also aiding. Should any vapors escape between the flanges 33 and 17, they will be deflected inwardly by the circumferential baffle-plate 19—20—21, and pass into the space between the chimneys 80 through the holes in the outer chimney. It is desirable that a lip 34 or other guide be formed on or connected to the elbow 27 and contact with the ledge 16 in order that the fuel will flow down at a constant rate and 85 not in drops. Surrounding the burner is a frusto-conical shield 36 which prevents currents of air from affecting the flame, said shield having small legs 37 and 38 on its inner surface to engage the baffle-ring 20 90 and thus position the shield.

To ignite the burner, the valve is opened so that a small amount of fuel can flow into the trough and saturate the asbestos ring 15. A flame is then applied to the ring which 95 causes the fuel to ignite and the inner chimney 1 to be heated very quickly and with it the fuel trough. By forming the trough and inner chimney of the same piece of metal, or of two pieces soldered or welded 100 together so as to be integral in effect, the heat applied to the inner chimney will be transmitted almost instantly to the fuel trough, resulting in the fuel being quickly evaporated and ignited. The outer chimney 105 also transmits its heat to the trough because it fits within the flange 13.

When the ledge 16 is integral with the trough, the fuel as it flows from the elbow 27 is heated at once. It flows through the 110

small holes in the lower end or under the lower end of the outer chimney into the trough and then burns between the chimneys, air passing to the flame through the holes in the chimneys 1 and 3. If the fuel is fed in sufficient quantities to cause the flame to extend above the top 5, air will pass to the inside of this flame from the pipe 4. By reason of the peculiar construction of 10 this burner a full fire can be obtained in about one third of the time required by burners of the usual construction. The flame can be absolutely controlled by the valve 28, because the trough is at such a 15 high temperature that there is no accumulation of the heavier portions of the fuel, all of the fuel being consumed as it is fed to the burner.

The proportions and details of the 20 construction can all be modified by those skilled in the art without departing from the spirit of my invention as set forth in the claims.

I claim:—

1. In a hydro-carbon burner, the 25 combination of a cylindrical perforated inner chimney and a fuel trough integral therewith, said trough having a cylindrical flange on its outer edge, a top for the inner chimney, an outer cylindrical chimney extending 30 down within the flange, an annular ledge on the trough, a cover for the ledge, means for delivering liquid fuel onto the ledge, and an outer shield for said burner.

2. In a hydro-carbon burner, the 35 combination of cylindrical perforated outer and inner chimneys, a trough connecting to the inner chimney and having a flange extending up in engagement with the outer chimney and having an outwardly extending 40 ledge at its upper edge, and a pipe for delivering liquid fuel to the ledge in such a manner as to prevent the forming of drops of fuel at the discharge end of the pipe.

3. In a hydro-carbon burner, the 45 combination of two perforated chimneys and a fuel trough extending from the lower end of the inner chimney to the lower end of the outer chimney and having an outer flange extending up around the lower end 50 of the outer chimney, a ledge extending around the outer chimney above said flange and having an upturned outer edge, a cover for the ledge, and a liquid fuel conveyer mounted adjacent the ledge to discharge the 55 fuel thereon in such a manner as to prevent the forming of drops of fuel at the discharge end of said conveyer.

4. In a hydro-carbon burner, the 60 combination of a perforated inner chimney and a fuel trough connected thereto, an outer perforated chimney mounted in said trough, a ledge integral with the trough extending around the outer chimney, a cover for the trough, means connected to said trough to 65 feed liquid fuel thereto for said burner, and

means for causing fuel vapor which may escape from the trough to pass inwardly through perforations in the outer chimney.

5. In a hydro-carbon burner, the combination of a cylindrical perforated inner 70 chimney and a fuel trough integral therewith, an outer chimney mounted in said trough, a ledge integral with the trough extending around the outer chimney, means to guide liquid fuel onto said ledge, and an 75 annular baffle plate connected to said outer chimney and extending downwardly and outwardly over said trough.

6. In a hydro-carbon burner, the combination of a cylindrical perforated inner 80 chimney and a fuel trough integral therewith, an outer perforated chimney mounted in said trough, a ledge integral with the trough extending around the outer chimney, a cover for the ledge, means connected 85 to said cover and contacting with the ledge to feed liquid fuel onto the ledge for said burner, and means for causing fuel vapor which may escape from the trough to pass inwardly through perforations in the outer 90 chimney.

7. In a hydro-carbon burner, the combination of a cylindrical inner chimney and a fuel trough connected thereto, an outer chimney mounted in said trough, a ledge integral with the trough extending around the outer chimney, and a conveyer to guide liquid fuel to the ledge in such a manner as to prevent the forming of drops at the 95 end of the conveyer.

8. In a hydro-carbon burner, the combination of two concentric perforated cylindrical chimneys and a fuel trough integral with one of them into which the other chimney fits tightly, means to feed liquid fuel 105 to the trough, a top for the inner chimney, an open ended tube extending downwardly from said top, an imperforate ring in the space between the inner chimney and said tube near their upper ends, and a second 110 ring in said space near the lower end of the tube and having passages for air.

9. In a hydro-carbon burner, the combination of a cylindrical inner chimney and a fuel trough integral therewith, an outer 115 chimney supported by said trough, a ledge integral with the trough and inner chimney extending around the outer chimney, and a conveyer to guide liquid fuel to the ledge where it may be vaporized by the heat conveyed from the inner chimney by the 120 trough.

10. In a hydro-carbon burner, the combination of concentric perforated inner and outer chimneys, a fuel trough connected to 125 the inner chimney and into which the outer chimney loosely extends, a cover for the fuel trough extending around the outer chimney, means to convey fuel to the trough, and means secured to the lower end of the 130

outer chimney to cause fuel vapors escaping between the cover and the outer chimney to pass through perforations in the lower end of the outer chimney to the space between the chimneys.

11. In a hydro-carbon burner, the combination of a cylindrical inner chimney and a fuel trough integral therewith, an outer chimney supported by said trough, a ledge 10 integral with the trough and inner chimney extending around the outer chimney, a conveyor to guide liquid fuel to the ledge where it may be vaporized by the heat conveyed from the inner chimney by the trough, and 15 means for causing the fuel vapor which may escape from the trough or ledge to pass inwardly through perforations in the outer chimney.

12. In a hydro-carbon burner, the combination of cylindrical perforated inner and 20 outer chimneys, a trough connected to the inner chimney and supporting the outer chimney, a ledge integral with the trough extending around the outer chimney above

the lower end thereof, means to feed fuel to 25 the trough, an inwardly sloping cover for the trough, and a cylindrical asbestos wick in the trough between the chimneys of such a height that its upper edge is above the inner edge of the ledge on the trough. 30

13. In a hydro-carbon burner, the combination of perforated inner and outer chimneys, a trough connected to the inner chimney and extending up around the lower end of the outer chimney, means to convey fuel 35 to said burner, and means secured to the lower end of the outer chimney to cause fuel vapors escaping from said trough around the outer chimney to pass through perforations in the lower end of the outer 40 chimney to the space between the chimneys.

In testimony whereof I sign this specification in the presence of two subscribing witnesses.

WILLIAM J. BEST.
